UNITED STATES PATENT OFFICE.

WALTER H. WHITTIER, OF GRAND RAPIDS, MICHIGAN, ASSIGNOR TO GRAND RAPIDS
REFRIGERATOR CO., OF GRAND RAPIDS, MICHIGAN, A CORPORATION OF MICHIGAN.

COUPLING-RING FOR REFRIGERATOR-LININGS.

1,028,310.

Specification of Letters Patent.

Patented June 4, 1912.

Application filed February 23, 1912. Serial No. 679,403.

To all whom it may concern:

Be it known that I, WALTER H. WHITTIER, a citizen of the United States of America, residing at Grand Rapids, in the county of Kent and State of Michigan, have invented certain new and useful Improvements in Coupling-Rings for Refrigerator-Linings; and I do hereby declare the following to be a full, clear, and exact description of the invention, such as will enable others skilled in the art to which it appertains to make and use the same.

My invention relates to improvements in coupling rings for refrigerator linings and its object is to improve upon the device shown in patent issued to me No. 970,672, dated Sept. 20, 1910, and its object is to provide a device adapted to be made of sheet metal and more easily adapted to any irregularity in the flanges, to provide the same with improved means for retaining the same in place and to provide the same with various new and useful features hereinafter more fully described and particularly pointed out in the claims reference being had to the accompanying drawings, in which:

Figure 1 is a perspective view of my improved coupling ring and adjacent portions of the lining; Fig. 2 a plan view of the ring with portions broken away; Fig. 3 a detail of a portion of the same in elevation; Fig. 4 an enlarged broken sectional detail taken transversely of the ring on line 4-4 of Fig. 2; and Fig. 5 a similar view through the ends of the ring on line 5-5 of Fig. 2.

Like numbers refer to like parts in all of the figures.

1 represents a portion of a refrigerator lining adjacent to an opening in the wall of the refrigerator, this lining being provided for opposite sides of the wall and provided with flanges 2 extending within the opening in the wall (the refrigerator wall being omitted herein). These flanges are preferably of such width that when in place in the refrigerator they leave a space therebetween to receive the outwardly extended margin of the ring.

50 My improved ring consists of a sheet metal structure having the inner portion 3 slightly convex toward the interior of the opening in which it is placed and the outer portions 4 folded upon the outside of the inner portion. These rings are preferably

made to fit elongated openings semi-circular at the ends and having parallel sides. The edges of the material are extended outward at the ends to form a circumferential rib as at 5 and at the sides of the ring are folded in reverse position upon the folded portions 4 as at 5^a to form channels to receive the flanges 2 of the linings. The ring is also preferably provided with a coupling plate 7 where the ends are joined to assist in holding the same in alinement and to more completely close the opening where the ends abut against each other, but this coupling is not important and can be omitted as preferred. The outer portions of the portion 4 are also formed somewhat concave as at 6, to secure more intimate contact of the folded margins of the ring with the flanges 2.

When the device is assembled as illustrated in Figs. 4 and 5 the ring forms a smooth rounded symmetrical lining to the opening and is effectually retained in place therein by engagement of the edges of the flanges 2 with the portions 4 and 5 of the ring.

What I claim is:

1. A coupling ring for refrigerator linings, comprising a sheet metal structure having a middle portion forming a lining for an opening, marginal portions folded on the outside of the middle portion and outwardly extended edge portions forming a circumferential rib or flange on the outside of the ring.

2. A coupling ring for refrigerator linings, comprising a sheet metal structure having a middle portion forming a lining for an opening, marginal portions folded on the outside of the middle portion and an edge portion outwardly extended to form retaining means for the ring.

3. A coupling ring for refrigerator linings, comprising a middle portion forming a lining to an opening, marginal portions folded upon the outside of the middle portion and edge portions refolded upon the marginal portions to form channels adapted to receive flanges on the refrigerator linings.

4. A coupling ring for refrigerator linings, comprising a sheet metal structure having a middle convex portion forming a lining for an opening formed semi-circular at the ends and parallel at the sides, marginal portions folded upon the outside of the middle portion, edge portions extended outward

opposite the ends and folded upon the marginal portions opposite the sides to form channels adapted to receive flanges on the refrigerator linings.

5. A coupling ring for refrigerator linings, comprising a sheet metal ring having a middle portion to form a lining for an opening and edge portions upon the outside of the middle portion adapted to enter be-

tween the flanges of a refrigerator lining to 15 hold the ring in place.

In testimony whereof I affix my signature in presence of two witnesses.

WALTER H. WHITTIER.
